PAIR OF SUN GLASSES

Mabel V. Tilton, Brooklyn, N. Y.

Application August 31, 1955, Serial No. 37,738

Term of patent 7 years

(Cl. D57—1)

FIG. 1

FIG. 2

Fig. 1 is a front perspective view of a pair of sun glasses showing my new design; and

Fig. 2 is a side perspective view thereof.

The dotted lines shown in Fig. 1 are for illustrative purposes only.

I claim:

The ornamental design for a pair of sun glasses, as shown and described.
